UNITED STATES PATENT OFFICE

2,366,542

CIRCUIT MAKER AND BREAKER

Joseph X. Mathieu, Pittsfield, Mass., assignor to
 General Electric Company, a corporation of
 New York

Application October 22, 1942, Serial No. 462,946

10 Claims. (Cl. 200—5)

This invention relates to circuit makers and breakers and more particularly to an improved compound arcing duty contactor which is particularly adapted for use with a certain type of load ratio control circuit.

By "load ratio control" is meant the changing of the ratio of a transformer by tap-changing means without interrupting the transformer load current. In many load ratio control circuits the actual tap-changing or ratio adjusting is done by means of non-arcing duty switches and the current interrupting or arcing duty is performed by separate switches. In a particular circuit of this type forming the subject matter of Patent No. 2,112,064, granted March 22, 1938 on an application of L. F. Blume and assigned to the assignee of the present application, the arcing duty is performed by a compound switching arrangement utilizing a pair of non-arcing duty selector switches and a single arcing duty switch.

In accordance with this invention there is provided a novel and simple combination of arcing duty switch and non-arcing duty selector switches which is particularly adapted for use in the circuit of the Blume patent. It is characterized by a compact structure in which all of the switches are operated by a single cam and no more than two cam followers are employed. Furthermore, the arcing duty switch is a multi-break switch which actually consists of at least two separate and distinct sets of contacts which open and close substantially simultaneously. One advantage of a multi-break arcing duty switch is that it increases the current interrupting ability. Another advantage is that a suitable impedance, such, for example, as a resistor, may be connected in parallel with one set of arcing duty contacts so that the benefits of the novel resistor-saturable reactor switching described in a copending application of L. F. Blume, Serial No. 462,945, filed October 22, 1942 and assigned to the assignee of the present application may be obtained.

An object of the invention is to provide a new and improved compound circuit maker and breaker.

Another object of the invention is to provide a new and improved compound arcing duty contactor for load ratio control circuits.

A further object of the invention is to provide a new and improved load ratio control switching arrangement.

The invention will be better understood from the following description taken in connection

with the accompanying drawing and its scope will be pointed out in the appended claims.

In the drawing Fig. 1 is a perspective view of an embodiment of the invention in which all of the switches or pairs of contacts are closed and in which the electrical connections thereof in a load ratio control circuit are shown, and Fig. 2 is another perspective view showing the arcing duty contacts and one of the non-arcing duty selector switches open and the other selector switch closed.

Referring now to the drawing and more particularly to Fig. 1, a pair of terminals 1 and 2 are connected respectively to separate contact fingers 3 and 4 of a non-arcing duty ratio adjuster 5 for a transformer whose multi-tapped winding is shown at 6. Interposed between each terminal and its associated contact finger is one-half of a split reactor 7. This comprises a pair of equal windings on a common core. It serves the dual purpose of an autotransformer for giving main transformer circuit voltages intermediate the voltages of the separate taps and a reactor for preventing short circuiting of the tap-to-tap voltage of the winding 6.

Ordinarily it is desirable to keep all arcing contacts for switches outside of the tank containing the windings and insulating liquid of a power transformer and to that end the terminals 15 of the switching arrangement are mounted on insulating bushings 8 and 9 extending through openings in the transformer casing. Pivotaly mounted on the terminals 1 and 2 are non-arcing duty selector switch arms 10 and 11 which are 20 adapted to be moved into and out of engagement with fixed contact terminals 12 and 13 respectively. These contacts are permanently connected together to one conductor 14 of the main circuit for the winding 6, the other conductor 25 of which is shown at 15.

For operating the movable contact arms 10 and 11 there is provided a cam 16 which by means of a shaft 17 is interlocked with the ratio adjuster 5 so that the two are maintained in the proper relation to each other. Cam 16 has equal radii in all directions and its face consists of a groove having an offset portion in the axial direction. Fitted in this groove along angularly displaced radii of the cam are a pair of rollers or cam followers 18 and 19 which are connected through suitable cranks and linkages 20 and 21 to the respective switch arms 10 and 11.

The cam 16 has a normal position in which both of the switches 10—12 and 11—13 are closed. A complete rotation of this cam from its normal

position will open one switch and then reclose it, and then will open the other switch and then reclose the latter, the order in which the switches operate depending upon the direction of rotation of the cam.

A feature of the above-described cam face and cam follower relationship is that the same portions of the cam face move both cam followers in the same direction. Thus, although the cam followers are displaced along substantially diametrically opposite radii of the cam, nevertheless the same portion of the cam face which causes downward movement of one cam follower also causes downward movement of its diametrically opposite follower and conversely the same portion of the cam face which causes upward movement of one cam follower causes upward movement of the other cam follower. This feature is used to cause operation of a multi-break arcing contactor by each of the cam followers.

The multi-break arcing duty contactor comprises a pair of arcing duty contacts 22 and 23 carried respectively on pivotally mounted insulating arms 24 and 25. The contacts 22 and 23 are electrically interconnected by a conductor 26 and the insulating arms 24 and 25 which carry them are mechanically tied together by a rigid bar 27. The insulating arms are mounted on members 28 and 29 which are loosely mounted on the shafts of the respective cam followers 18 and 19. Springs 30 and 31 serve to bias the contacts 22 and 23 into engagement with their respective co-operating fixed contacts 1 and 2.

Each of the cam followers and their associated members 28 and 29 have interlocking projections 32 (shown more clearly in Fig. 2) whereby operation of the cam followers in the direction to open their associated non-arcing duty selector switches will, after those selector switches have first opened, cause simultaneous opening of the arcing duty contactor switches 1-22 and 2-23. Continued rotation of the cam 16 will eventually cause reclosure of the non-arcing duty switches and the springs 30 and 31 will reclose the arcing duty contactor switches.

The operation of the illustrated embodiment of the invention is as follows: With the parts as shown in Fig. 1 all of the switches or cooperating pairs of contacts are closed so that the load current of the winding 6 divides substantially equally between the branch conductors or conducting paths to which the ratio adjusters 3 and 4 are respectively connected. The voltage difference between the taps to which the contact fingers 3 and 4 are connected causes a circulating current to flow through the path which, starting with the contact finger 3, may be traced as follows: The left-hand half of the split reactor 7, the selector switch 11-13, the selector switch 10-12, the right-hand half of the split reactor 7, the contact finger 4 and back to the contact finger 3 through the main winding 6. This current is limited to a value which does not exceed the overload current rating of the winding 6 by the reactance of the split reactor, whose two windings are so arranged that they act cumulatively on their common core when such a circulating current flows.

The rotation of the shaft 17 in one direction will cause the following sequence of operation. First the selector switch 11-13 will open, then the multi-break arcing duty switch 1-22-23-2 will open, then the contact finger 4 will move to the left so as to make connection with the same tap to which the contact finger 3 makes con-

nection, then the arcing duty switch 1-22-23-2 will close and then the selector switch 11-13 will close. This corresponds to one-half of a complete revolution for the cam 16. During the next half revolution the selector switch 10-12 will first open, then the arcing duty switch will open, then the contact finger 3 will move to the left into contact with the left-hand tap, then the arcing duty switch will reclose and finally the selector switch 10-12 will reclose. If, on the contrary, the shaft 17 had been rotated in the opposite direction, then the selector switch 10-12 would have first opened followed by the opening of the arcing duty switch and the movement of the contact finger 3 to the right into engagement with the same tap to which the contact finger 4 is shown as making connection. The selector switch 10-12 and the arcing duty switch would then reclose in the order mentioned. This would take place during the first half revolution of the cam and during the second half revolution the selector switch 11-13 would first open, then the arcing duty switch would open, then the contact finger 4 would move to the right into contact making relationship with the next right-hand transformer tap, then the selector switch 11-13 and the arcing duty switch would reclose in the order mentioned. This covers a complete cycle of operation of the parts for either direction of operation of the shaft 17.

Whenever either selector switch opens all the current flowing through it immediately transfers to the arcing duty switch so that the single arcing duty switch serves to interrupt the current in each of the branch circuits as long as the appropriate selector switch has previously been opened. Consequently, the operation of the contact fingers 3 and 4 is carried out without any arcing as the circuits of these contact fingers have previously been interrupted.

The current interrupting capacity of the arcing duty switch can be increased by connecting a resistor 33 across either one of its sets of contacts. As shown, it is connected across the contacts 1-22. With this arrangement the arc drawn between the contacts 1-22 will go out before the arc drawn between the contacts 23-2 and the current in the arc drawn between the contacts 23-2 will all flow through the resistor 26 as well as through one-half of the split reactor 7. This so changes the phase relation between the arc current and the arc voltage that arcs of higher volt-amperes can readily be extinguished when the resistor 26 is used than when it is not used. This latter feature is described and claimed broadly in the above-mentioned copending Blume application.

The position of the ratio adjusting contact fingers 3 and 4 in Fig. 1 is known as the half cycle position of such a ratio adjuster. In this position the split reactor 7 not only functions to limit the circulating current but it also serves as an autotransformer which makes the voltage of the main conductor 14 halfway between the voltages of the taps to which the contact fingers 3 and 4 are connected. When the contact fingers make engagement with the same tap the position is known as the full cycle position. In this position there is substantially no voltage drop in the reactor 7 because there is no voltage to produce a circulating or magnetizing current and the electromagnetic effects of the load current cancel each other.

While there has been shown and described a particular embodiment of this invention, it will be obvious to those skilled in the art that various

changes and modifications can be made therein without departing from the invention and, therefore, it is aimed in the appended claims to cover all such changes and modifications as fall within the true spirit and scope of the invention.

What I claim as new and desire to secure by Letters Patent of the United States is:

1. In combination, a cam, means for selectively rotating said cam about its axis in either direction, a pair of cam followers disposed on angularly displaced radii of said cam, separate switches actuated by each of said cam followers, and a third switch having actuating means disposed in the path of movement of members associated respectively with each of said cam followers.

2. The combination as set forth in claim 1 in which said third switch is a multi-break switch.

3. In combination, four pairs of circuit making and breaking contacts, a single cam, a pair of cam followers therefor disposed on angularly displaced radii thereof, mechanical connections between said cam followers and two of said pairs of contacts for opening and closing each of them once for each revolution of said cam, and means actuated by said connections for opening the two remaining pairs of contacts after each of the first-mentioned two pairs of contacts is opened and for closing said two remaining pairs of contacts before each of said first-mentioned two pairs of contacts is closed.

4. In combination, a cam, means for rotating said cam, a pair of followers for said cam actuated in the same direction by the same portions of the face thereof and disposed on angularly displaced radii thereof, a pair of switches operated respectively by said cam followers, and a third switch actuated by each of said cam followers.

5. The combination as set forth in claim 4 in which said third switch opens after each of said pair of switches opens and closes before each of said pair of switches closes.

6. In combination, a cam, means for rotating said cam, a pair of followers for said cam actuated in the same direction by the same portions of the face thereof and disposed on angularly displaced radii thereof, a pair of switches operated respectively by said cam followers, a third switch actuated by each of said cam followers, and a circuit having a pair of effectively parallel branch conductors, the switches of said pair being connected respectively in circuit with said branch conductors, said third switch being connected between said branch conductors.

7. In combination, a cam having a normal position, means for selectively rotating said cam in either direction from said normal position, a pair of cam followers disposed on substantially

diametrically opposite sides of said cam, a pair of normally closed switches connected respectively to said cam followers so that each of said switches will be opened and reclosed by a complete revolution of said cam, the order of operation of said switches being determined by the direction of rotation of said cam, a normally closed switch, a spring for biasing said last-mentioned switch closed, said last-mentioned switch

5 having an actuating member so disposed in the path of movement of each of said pair of switches that the opening of either of said pair of switches is followed by the opening of said last-mentioned switch and the closing of either of said pair of switches is preceded by the closing of said last-mentioned switch.

8. In combination, a cam having a normal position, means for selectively rotating said cam in either direction from said normal position, a pair of cam followers disposed on substantially diametrically opposite sides of said cam, a pair of normally closed non-arcing duty switches connected respectively to said cam followers so that each of said switches will be opened and reclosed by a complete revolution of said cam, the order of operation of said switches being determined by the direction of rotation of said cam, a normally closed arcing duty switch, a spring for biasing said last-mentioned switch closed, said last-mentioned switch having an actuating member so disposed in the path of movement of each of said pair of switches that the opening of either of said pair of switches is followed by the opening of said last-mentioned switch and the closing of either of said pair of switches is preceded by the closing of said last-mentioned switch.

9. In a load-ratio-control circuit of the double contact finger ratio adjuster type, in combination, separate sets of non-arcing duty selector contacts, a common set of arcing duty contacts, a single cam, a pair of cam followers on angularly displaced radii thereof, said cam followers being connected to operate said sets of selector contacts respectively, and means responsive to the motion of either cam follower for controlling the operation of said arcing duty contacts.

10. In a load-ratio-control circuit of the double contact finger ratio adjuster type, in combination, separate sets of non-arcing duty selector contacts, a common set of multiple break arcing duty contacts, a single cam, a pair of cam followers on angularly displaced radii thereof, said cam followers being connected to operate said sets of selector contacts respectively, and means responsive to the motion of either cam follower for controlling the operation of said arcing duty contacts.

JOSEPH X. MATHIEU.
